TO W. H. MINER, INC., A CORPORATION OF DELAWARE

DOOR-OPERATING MECHANISM

Application filed February 18, 1924. Serial No. 693,647.

This invention relates to improvements in door operating mechanisms. In the operation of refrigerator cars having swinging side doors, it is frequently found impossible to operate the doors to open and close the same, when the car is at the loading platform, due to the platform interfering with the operation. This difficulty is due to the obstruction offered by the projecting parts of the usual door operating mechanism, which, as most commonly employed, includes a vertically disposed shaft mounted on one of the doors and having its opposite ends extending beyond the upper and lower edges of the door and engageable with keepers mounted at the top and bottom of the opening in the door frame. This difficulty exists even though the loading platforms are properly designed to normally provide sufficient clearance for the door operating mechanism projecting from the bottom edge of the door, as the amount of clearance actually provided in practice is inadequate to take care of the unavoidable variations in height above the top of the rails of the bodies of different cars, and variations in height above the tops of the rails of the body of the same car under different conditions depending on whether the car is empty or loaded, it being evident that the truck springs will be compressed to a greater degree when the car is loaded than when empty, thereby frequently lowering the body to such an extent that the door operating mechanism will project below the level of the upper surfaces of the loading platforms.

The principal object of the invention is to provide a refrigerator car door construction having an operating mechanism so arranged as to entirely overcome the defects hereinbefore pointed out.

Another object of the invention is to provide a simple and efficient arrangement of door operating mechanism, especially adapted for refrigerator cars, for forcing the doors tightly closed and holding the same locked and which will also be effective for starting the door opening operation.

A more specific object of the invention is to provide a mechanism of the character in-

dicated, designed for operating swinging doors, including an operating shaft journaled on one of the doors and coacting with a pair of keepers, wherein the keepers are mounted respectively on the door frame, at the top of the door opening and on the other coacting door adjacent the lower end thereof.

Other objects and advantages of the invention will more clearly appear from the description and claims hereinafter following.

In the drawing, forming a part of this specification, Figure 1 is a side elevation of a portion of a refrigerator car, showing my improvements in connection therewith, the view being partly broken away to better accommodate the same to the sheet of the drawing. And Figure 2 is a horizontal, sectional view corresponding substantially to the line 2—2 of Figure 1.

In said drawing, the car is shown as provided with a door frame 10 and two pivoted doors 11 and 12 having meeting beveled edges in the usual manner. As is customary in refrigerator cars, insulation or packing 13—13 is employed between the meeting edges of the doors and car frame and between the meeting edges of the doors themselves, but inasmuch as the form or character of the insulation forms no part of the present invention, the same need not be described in detail.

As shown, the improved door operating mechanism comprises, broadly, an operating shaft A, provided with two end castings B—B, and an operating handle C; upper and lower keepers D—D coacting with the castings B—B; and a pair of upper and lower bearing brackets E—E.

The operating shaft A is in the form of a flat bar of substantially rectangular cross-section having the castings B rigidly secured thereto in any suitable manner.

The castings B are disposed respectively at the upper and lower ends of the shaft A. Each of the castings B, as shown, is preferably in the form of a crank member having a cylindrical journal portion 14 alined with the shaft A and an offset cylindrical end portion 15 of relatively smaller diameter forming the crank member proper. Each casting B is formed with a head 16 which is verti-

cally slotted to receive the corresponding end of the shaft A, to which it is riveted. The casting B, which is secured to the lower end of the shaft A, is of greater length than the casting B at the upper end of the shaft and has an arm 17 laterally projecting therefrom to which is pivoted the operating handle or lever C, the arm 17 being so disposed as to project nearly diametrically opposite to the crank portion 15.

The bearing brackets E—E which are of like construction are secured to the door 12 adjacent the free edge thereof, one of the brackets being disposed closely adjacent the top edge of the door and the other being disposed below the center of the door, spaced an appreciable distance from the lower edge thereof. Each of the brackets extends beyond the free edge of the door 12 as clearly shown in Figure 1, being provided with a bearing portion 18 outwardly offset with reference to the door 12 and adapted to rotatably receive the journal portion 14 of the corresponding casting B.

The upper and lower keepers D are of substantially like construction, each being in the form of a casting having an outwardly offset central portion 19 provided with a slot or double acting cam groove 20. The lower keeper D is mounted on the door 11 adjacent the free edge thereof, being so disposed as to cooperate with the lower crank arm 15, and the upper keeper D is mounted on the door frame immediately above the door 11, being so disposed as to cooperate with the upper crank arm 15.

The door first closed is the door 11, and to retain the same in closed position while the door operating mechanism is manipulated, a latch member F is preferably provided, although the same is not absolutely essential in that the operating mechanism will properly perform its function with the latch member F omitted. The latch member F is pivotally mounted on the door frame adjacent the lower edge of the door 11 and is adapted to cooperate with a plate 21 fixed to the lower outer corner of the door, the member F being provided with a suitable cam face designed to force the door 11 from a nearly closed to a fully closed position.

The handle C is adapted to be locked as shown in Figure 1, by any suitable locking device, as indicated at 22 and sealed in any suitable manner, customary on railroad cars.

In operating my invention, the door 11 will first be moved to closed position and secured by the latch F. The door 12 is then swung inwardly, the shaft A being first moved to such a position that the crank arms 15 at the opposite ends of the same will be disposed in a plane substantially at right angles to the plane of the door. While the door 12 is being moved toward closed position, the crank arms 15 enter the slots 20. After the crank

arms 15 have been engaged within the slots, the shaft A is rotated by swinging the handle C to the right to the position shown in Figure 1. Upon rotation of the shaft A, the members 15 will be guided by the keepers D and the door 12 forced to tightly closed position by the crank acting offset portions 15. The handle C is then locked to the device 22 and sealed in the usual manner.

To open the door 12, the handle C is swung outwardly away from the door as seen in Figure 1, thereby rotating the shaft A in the reverse direction to that just described. Rotation of the shaft A is continued until the members 15 clear the slots 20, during which action the crank portions 15 of the end castings B in cooperation with the grooves 20 of the keepers will have forced the doors 11 and 12 partially apart, whereupon the door 12 may be swung fully open. Upon releasing the handle C, the same will drop out of the way to the dotted line position indicated in Figure 1.

From the preceding description taken in connection with the drawing, it will be evident that I have provided a very simple and efficient door operating mechanism, which entirely overcomes the defects encountered in prior devices of this character, in that the operating shaft extends beyond the top edge of the door only and has the lower end thereof terminating short of the bottom of the door.

It will be evident that my improved door operating mechanism is adapted to be applied to doors of different dimensions varying in height, without making any change in the dimensions of the operating mechanism. In other words, due to the fact that the distance between the upper and lower keepers does not in any way depend on the height of the door, but depends directly on the length of the operating shaft, the door operating mechanism may be standardized so that a single size will suffice for all heights of doors, thus materially reducing manufacturing costs.

I have herein shown and described what I now consider the preferred manner of carrying out my invention but the same is merely illustrative and I contemplate all changes and modifications that come within the scope of the claims appended hereto.

I claim:

1. In a door operating mechanism, the combination with a member having a door opening and provided with a pair of pivoted doors; of a keeper secured to said member adjacent one edge of one of said doors; a second keeper secured to said last named door; an operating shaft rotatably carried by the other door and having actuating means thereon cooperating with both of said keepers to force said last named door either closed or open, one of said actuating means being disposed within the confines of the door and

the other actuating means projecting beyond the adjacent edge of the door into cooperating relation with the keeper means mounted on said member.

2. In a door operating mechanism, the combination with a member having a door opening and a pair of pivoted doors; of a keeper fixed to said member at the top of the door opening; a second keeper fixed to the door first closed; and operating means carried by the other door, said means engaging with both of said keepers to operate one of said doors to either open or close the same.

3. In a door operating mechanism, the combination with a member having a door opening and a pair of pivoted doors, one of which is adapted to be first closed; of a rotary operating shaft supported on the other door, said shaft having cranks at the opposite ends thereof; and means fixed to said member and the door first closed respectively, adapted to co-act with said cranks, said keeper on the member being disposed above said doors and the keeper on said door being disposed above the lower edge thereof, whereby upon rotation of said cranks, the door last closed is operated and forced against the other door.

4. In a door operating mechanism, the combination with a member having a door opening and a pivoted door for closing said opening; of a pair of keepers, one of said keepers being located above the lower edge of the door opening and the other above the upper edge of said opening; an operating shaft rotatably carried by the door along the free edge thereof and having actuating members thereon at opposite ends, one of said actuating members being disposed above the lower edge of the door and the other of said actuating members being disposed above the upper edge of the door, said actuating members respectively cooperating with said keepers to force the door either closed or open.

In witness that I claim the foregoing I have hereunto subscribed my name this 14th day of February, 1924.

STACY B. HASELTINE.
